C. W. OGLE

VALVE GRINDER

Filed March 24, 1921

FIG. 2.

FIG. 3.

FIG. 4.

FIG. 5.

Inventor:
Charles W. Ogle.
By H. G. Fletcher,
Atty.

Patented Oct. 27, 1925.

1,559,177

UNITED STATES PATENT OFFICE.

CHARLES W. OGLE, OF ST. LOUIS, MISSOURI.

VALVE GRINDER.

Application filed March 24, 1921. Serial No. 455,033.

To all whom it may concern:

Be it known that I, CHARLES W. OGLE, a citizen of the United States of America, and a resident of the city of St. Louis and State of Missouri, have invented certain new and useful Improvements in a Valve Grinder, of which the following is a specification.

The primary object of this invention is to provide an improved device for holding and operating tools that are to be revolved.

Another object of the invention is to provide an improved operating tool holder in which the actuating portion of the holder is reciprocated for operating the tools in a revolving direction.

A still further object of the invention is to provide improved means in a tool operating device in which means are provided whereby the stopping position of the tool holder can be changed.

Another still further object of the invention is to provide an improved operating holder for the revoluble tool holding element of a valve grinding device.

Other and further objects will appear in the specification and be specifically pointed out in the appended claims, reference being had to the accompanying drawings exemplifying the invention, and in which:

Fig. 1 is a plan view of this improved device.

Fig. 2 is a side elevation of Fig. 1 showing its application to a valve which is to be ground on its seat.

Fig. 3 is a vertical section taken on the line III—III of Fig. 2.

Fig. 4 is an inverted fragmentary sectional view taken on the line IV—IV of Fig. 2.

Fig. 5 is a sectional plan view taken on the line V—V of Fig. 2.

With reference to the accompanying drawings, 1 designates a guiding and holding element which is comprised of end members 2 and 3 and secured to said end members are guiding plates 4 and 5, said members being spaced apart and arranged therebetween is a revoluble member 6. Formed in each of the members 4 and 5 is a longitudinally extending slot 7 and adapted to be extended vertically through said slots which oppose one another is a tool holding socket 8, said socket at its lower end also being engaged in the bore 9 which is arranged centrally in the revoluble member

6, said socket bearing a key 10 for engagement in the key-way 11, which is formed in the wall of the bore 9.

The socket 8 is provided with an upwardly extending stem 12 which is slidably engaged therein at 13, said socket being turnably engaged within a hand gripping portion 14, said socket being held in engagement with said gripping portion by a pin 15 which is engaged within a groove 16 formed in the socket 8, the upper end of said stem extending from the upper end of the gripping portion 14 and forming a thumb engaging portion 17.

The revoluble member 6 is provided on its periphery with a spiral groove 18 and wound around said member within said groove is a cable 19 one of the extending ends of said cable being secured to the end member 2 by the set screw 20, the other extending end of said cable being secured to an adjustable draw bolt 21 by the set screw 22, said draw bolt being mounted in the end member 3, the threads of one end of said bolt being engaged in the adjusting handle 23, said handle at one end abutting the end member 3 and mounted on said draw bolt is a lock nut 24.

The socket 8 is provided on its lower end with a plurality of pairs of opposing notches 25, and in the operation of the device for valve grinding, which is the primary intent thereof, the shank end of the tool 26 is inserted within the socket 8 in which the cross pin 27 borne by the shank of the tool will be engaged within a pair of opposing notches 25 and the valve engaging end 28 of the tool which is formed similar to that of a screw driver, is engaged in a co-operative slot 29 formed in the valve 30, which is to be ground on its seat 31, the operator gripping with one hand the gripping portion 14 and with the other hand engages the handle 23 and pushes the guiding and holding member 1 back and forth and in so doing the cable 19 carried thereby on account of being wound around the member 6 will travel around said member thereby causing rotary movement to be imparted to said member and since the movements of the guiding and holding member 1 are reciprocatory alternating revolutions will be given to the member 6 and since the tool 26 is engaged to the valve 30 said valve will be alternately rotated on its seat, and the ap-

plication of emery or other suitable material between the valve and its seat will create the valve grinding.

When it is desired to change the stopping position of rotation of the valve which is created at the end of each stroke of the member 1, the thumb of the gripping hand of the operator is borne downwardly on the engaging end 17 of the stem 12 and lifting movement is applied to the hand gripping portion 14 and owing to the fact that the socket 8 is secured to the gripping portion 14 by the pin 15, the socket 8 will be elevated in which the engaged pair of notches 25 will be disengaged from the cross pin 27 of the tool 26. The member 1 is then moved so that the revoluble member 6 will be revolved without being effective towards turning the tool 26, the revolving of said member 6, however, being just enough to turn the socket 8 so that the cross pin 27 will be engaged by a different pair of notches 25 of said socket, when the gripping portion 15 is moved downwardly such shifting position of the socket relative to its engagement with the tool 26 providing for the stopping of the valve rotation being made at another point other than the previous stopping place, all of which is for the purpose of preventing a quantity of carbon from accumulating at a specific place between the valve and its seat.

For providing a take up to the cable 19 the lock nut 24 when loosened on the draw bolt 21 will permit the handle 23 when turned in a right hand direction to draw on said bolt and when the cable has been drawn tightly enough the nut 24 is then tightened against the end member 3.

For securing the revoluble member 6 to the socket 8 the head of the screw 32 borne by said member 6 is engaged in the recess 33 provided in the wall of said socket.

With the use of a device of this character for valve grinding, it is to be noted that a valve can be alternately revolved with rapidity and in which a valve can be ground on its seat in a very short space of time.

For preventing slipping of the cable 19 in the groove 18 of the member 6, said cable when being secured thereto is passed through an opening 34 formed in the member 6 before the winding of the cable in the groove 18 is begun, then opposing portions of the cable are engaged in respective recesses 35 and are then wound in the groove 18 towards each other as shown in Figs. 2 and 3, and in which an intermediate portion 36 of the cable is securely seated in the opening 34.

What I claim is:

1. In an operating tool holder, a reciprocable guiding member, a turnable element

located in said member having its axis slidably supported thereby, said element adapted to support a tool, and means secured adjacent each end of said member co-operable with said element for turning said element in alternate directions when said member is reciprocated. 65

2. An operating tool holder comprised of a turnable element adapted to hold a tool, a reciprocable holding member for said element being slidably related thereto said element bearing a tool securing socket, a cable secured at its ends to opposing portions of said member co-operably related to said element for revolving said element when said member is reciprocated, and means borne by said element for releasing said socket from its keyed position to the tool borne thereby so that said socket can be raised and turned 80 without turning the tool. 75

3. An operating tool holder comprised of a turnable element bearing a tool securing socket, a reciprocal holding member for said element provided with a slot through which said socket is mounted, a cable secured at its ends to opposing portions of said member and wound around said element for revolving said element when said member is reciprocated, and means provided for releasing said socket from its keyed position to the tool borne thereby so that said socket can be turned without turning the tool. 85

4. An operating tool holder comprised of a turnable element bearing a tool receiving socket, a hand gripping portion for turnably supporting said socket, a reciprocal holding member for said element provided with a slot through which said socket is mounted, and a cable secured at its ends to opposing portions of said member and wound around said element for revolving said element when said member is reciprocated. 95 100

5. An operating tool holder comprised of a turnable element bearing a tool receiving socket, a hand gripping portion for turnably supporting said socket, a reciprocal holding member for said element provided with a slot through which said socket is mounted, a cable secured at its ends to opposing portions of said member and wound around said element for revolving said element when said member is reciprocated, and means provided for adjusting said cable. 105 110

6. A revoluble member provided with a winding groove on its periphery, a cable to be wound in said groove, said member having a seating opening or passageway arranged parallel to the axis thereof for the reception of a portion of said cable. 115

CHARLES W. OGLE.
